UNITED STATES PATENT OFFICE.

FREDERICK M. FURBER, OF REVERE, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

BURNISHING-MACHINE.

1,284,303.

Specification of Letters Patent. Patented Nov. 12, 1918.

Application filed February 19, 1915. Serial No. 9,343.

To all whom it may concern:

Be it known that I, FREDERICK M. FURBER, a citizen of the United States, residing at Revere, in the county of Suffolk and State 5 of Massachusetts, have invented certain Improvements in Burnishing-Machines, of which the following description, in connection with the accompanying drawings, is a specification, like reference characters on 10 the drawings indicating like parts in the several figures.

This invention relates to burnishing machines, and particularly to burnishing machines employed in the manufacture of boots 15 and shoes for burnishing or "setting" the edge of the sole. This invention is especially concerned with that type of burnishing or edge setting machines in which the tool or "iron" is given a rapid to-and-fro 20 motion.

It is customary, in burnishing machines, to heat the iron in order to produce satisfactory work. Gas and steam have heretofore been used to heat the iron but have 25 proved unsatisfactory because of the unavoidable clumsiness of the construction, the uncleanliness and waste of heat and consequent expense and discomfort which attend their use, and for other reasons. It has 30 already been proposed to use electricity for the purpose of heating the irons of edge setting machines, but considerable difficulty in the development of such machinery has been experienced on the score of economy. 35 Electric energy is expensive, and the devices which have been proposed for using it in the type of machines described have been so wasteful that, for this reason among others, they have never gone into commercial 40 use. It is an important object of my invention to provide practical and economical means for the application of electric heat to a machine of this type which shall obviate disadvantages heretofore existing in such 45 electrically heated machines.

It is a further object of my invention to improve and simplify the construction of the machine disclosed in my Patent No. 1,107,282, Aug. 18, 1914, and to provide 50 for the electrical heating of the irons in said machine.

A feature of the invention is the provision of a socket for an electric unit, similar in shape to the member which is to convey 55 the heat from the unit to the burnishing tools, and arranged in close relation to it,

so that minimum surface for wasteful radiation is provided. This secures the desired economy in the use of the electric energy.

Another feature of my invention is a 60 novel construction of finger rest or hook, which is normally movable from operative position but which is locked in operative position by the operator.

A further feature of my invention is the 65 provision of novel and improved means for interchanging the operative positions of the tools carried by a multiple tool holder. A further feature is the provision of novel means for permitting resilient yielding of 70 the burnishing iron under the pressure exerted by the operator on the shoe whereby the iron may better follow the contour of the sole edge. In the embodiment shown in the drawings these two features are illustrated in combination, the resilient member 75 acting also as a locking bolt for the shifting tool holder.

The invention also comprises other features including certain details of construction and combinations and arrangements of parts which will be later described and claimed.

In the accompanying drawings which show a preferred embodiment of the invention in a vibrating tool edge setting machine,

Fig. 1 is a side elevation of the machine,

Fig. 2 is a plan view of the oscillating 90 tool carrying mechanism, with certain overhanging parts cut away,

Fig. 3 is a front elevation of the finger hook,

Fig. 4 is a central longitudinal section, on 95 a larger scale,

Fig. 5 is an enlarged front elevation, with the unit carrying pocket in section,

Fig. 6 is an enlarged section of the unit,

Fig. 7 is an enlarged detail of the finger 100 hook, and

Figs. 8, 9 and 10 are details showing the fastening of the ends of the resistance wire.

The V-shaped frame 10 has at its ends bearings 11, in which the oscillating shaft 105 12 is supported. This shaft carries the tight pulley 13 and loose pulley 14, on which the belt 15 is shifted by the shifter 16. The tight pulley 13 carries the casing 17 in which runs a mechanism which transforms 110 the rotary motion of the pulley 13 into an oscillatory motion of the shaft 12. This

mechanism forms the subject-matter of my application for Patent No. 870,313, filed Nov. 4, 1914, and need not be further described here.

5 The shaft 12 carries a burnishing mechanism at each end, and as these are identical, only one will be shown and described. A hole 18 is formed in the end of the shaft 12, and a small socket 19 is made at the 10 bottom of it. A bolt 20, having a small socket 21 at its rear end slides in the hole 18. A strong spring 22 has its ends mounted in the sockets 19 and 21, and thereby 15 resiliently supports the bolt 20 and prevents it from turning. Threaded to the bolt 20 is a bolt 23, having a shoulder 24 and a reduced capstan head 25 at its front end. The capstan head 25 carries a lug 26.

20 The oscillating head or rocker frame 27 having at its lower front a stop 27^a, is slipped over the end of the shaft 12 and fastened by the set screw 28. It has at its front a hole 29 fitting the capstan head 25. The shoulder 24 rests against the inside 25 edge of the hole 29 and the capstan head 25 projects through it, the head 27 thus confining the bolt 23 in the hole 18 while permitting it to rotate and to recede. The rotation of the bolt 23 adjusts the effective 30 length of the combined bolts 20, 23 by means of the thread and thereby adjusts the tension of the spring 22.

Pivoted to the rocker frame 27 at 30 is a carrier 31, having at its lower rear a stop 35 31^a, which has two extensions 32 straddling the lower end of the rocker frame and extending behind the pivot. A spring 33 is mounted on the extensions 32 and bears against the back of the rocker frame 27 in 40 order to support resiliently the carrier 31 against downward rotation about its pivot 30. The stops 27^a and 31^a contact when the carrier 31 is tilted counter-clockwise (in Fig. 4) and limit its tilting movement. The carrier 31 is split at 34, forming a cylindrical bearing 34^a the cap 35 of which is attached by the screws 36.

50 Mounted in the bearing 34^a is a spindle 37 of the tool holder. The spindle carries at its top the cap 38, and at its bottom the foot 39. The former has two upwardly projecting lugs 40, forming a slot 41, and two oppositely disposed notches 42, adapted to engage the lug 26. It will be clear that 55 the spring 33 holds the carrier 31 upright and keeps one notch 42 engaged with the lug 26 when the spindle 37 is properly placed, thus locking the tool holder against rotation. The foot 39 carries two little 60 spindles 43, upon which the shank and fore-part irons 44, 45 are held by the springs 46. It will be evident that when sufficient pressure is exerted by the operator on the shoe, the carrier 31 will be rotated clockwise in Fig. 1, forcing the bolts 20, 23,

backward and compressing the spring 22. The irons 44, 45 are thus resiliently supported and are enabled to follow the curved contour of the sole edge better than irons which are arranged to move only in arcs of 70 circles.

5 The carrier 31 are two uprights 47, carrying binding posts 48 insulated by the fiber washers 49. The cap 35 has a cylindrical pocket 50 parallel to and 75 co-extensive with the spindle 37, in which an electric heating unit 51 is carried. The pocket 50 has two opposed slots 52 through its wall at its upper end, and the lead wires 53, covered with the insulating beads 54 80 pass through these slots and are attached to the upper end of the unit. The pocket 50 has a mica floor 50^a and the two beads which rest in the slots 52 are of mica instead of glass in order to resist the intense heat at 85 these points. The terminals 55 are fastened to the binding posts 48. It will thus be seen that the unit 51 is disposed co-extensive with the spindle 37 and as close thereto as is practicable, and that both are mounted in the same 90 mass of metal, so that the transfer of heat is easy and the radiating surface and consequent waste are reduced to a minimum. Current is supplied through the binding posts by the conductor 56, which leads to 95 a rheostat 57, the resistance of which is utilized to heat its base 58, carrying pins 59, on which spare irons 44 may be kept hot when not in use. Current is supplied to the rheostat through the terminals 60.

100 It should be noted that the slots 52 are as close as is practicable to the axis of oscillation of the shaft 12. The lead wires 53 are therefore subject to minimum vibration where they enter the unit 51. Thus breakage of the lead wires at this point, which is a serious objection to apparatus of this type heretofore used, is obviated.

105 The electrical unit itself is shown in Figs. 6, 8, 9 and 10. A nickel steel rod 61 has 110 mounted on its central portion an externally threaded lava core 62. Below the core is a nickel steel washer 63 and below this is a mica washer 64 of larger diameter than the main body of the unit, and adapted to fit 115 closely in the pocket 50. A steel washer 65 is mounted below the mica washer 64 and the rod 61 is headed at this end. Above the lava core 62 is mounted a lava ring 66 of smaller diameter than the lava core and outside of 120 this is mounted a nickel steel ring 67 of the same diameter as the lava core, and of the same width as the lava ring 66. Above these two rings is a mica washer 68 like the mica washer 64. A head 69 is formed on the 125 rod 61. A resistance wire 70 is wound in the thread on the lava core 62, its ends are placed in slots 71 in the nickel steel members 63, 67, and the sides of the slots are then upset upon them. The lead wires 53 130

are brazed to the head 69 and the ring 67. The nickel steel has a very small co-efficient of expansion for heat, and the rod 61, with its two heads compresses the members it carries and supports them longitudinally, while the resistance wire supports the lava core laterally. Thus a strong unit, resistant to shocks and vibration, is secured.

A lever 72 is pivotally mounted at 73 in the frame 10. It is forked at its upper end and carries a pivoted pin 73 in the fork.

This pin has a threaded hole 74 at its center and in this threaded hole is mounted a coarse pitched screw 75, with a screw-driver end

76. The rear face of the pin 73 is flat and engages a stop 77 on the cap of the bearing 11. When in contact with this stop the pin 73 is so turned that the screw driver end 76 is just above the slot 41. A spring 78

normally holds the pin 73 against the stop 77. When pressure is exerted against the head 79, at the lower end of the lever, the pin 75 is swung down and the screw driver end 76 engages the slot 41. Thus a combined thrust

25 and torque is exerted on the head 38 of the tool holder. The torque is resisted by the lock 26-42 and the thrust forces the carrier counter-clockwise in Fig. 1, about the pivot 30, against the spring 33 until the head 38

30 swings free from the lug 26 and the stops 27^a and 31^a contact. The torque is no longer resisted and begins to rotate the tool holder, the screw 75 meanwhile turning, as the pin 73 is forced down over it by the lever 72.

35 The lever 72 carries at its upper end a stop 80 which engages (see dotted lines in Fig. 2) the side 81 of the head 38, when the tool holder has turned approximately 180° and brought the other iron forward. Release of

40 pressure on the head 79 then permits the carrier 31 to be forced back by the spring 33 until the other notch 42 engages the lug 26, thus locking the holder in operative position again. It will be noted that the slot

45 41 is substantially in the center of oscillation of the shaft 12. Thus the engagement of the screw driver end 76 with the slot is made positive and certain.

The lower arm of the lever 72 carries a 50 finger hook or rest 82 mounted in a bearing. The rear end of the bearing has a stepped slot 83 and the finger hook carries a stepped collar 84. A spring 85 bears against the collar 84 and the lever 72 and thus forces

55 the hook backward until the collar 86 bears against the front of the lever 72. The step 87 of the collar 84 will just fit in the bottom step of the slot 83, but is normally held free of this bottom step by the spring 85. The

60 collar 86 is adjustable by means of the set screw 86' shown in Figs. 1, 3, 5, and the collar 84 is likewise adjustable by means of the set screw 84' (Figs. 1, 7). The operative position of the hook 82 may thus be 65 adjusted. The hook 82 may therefore nor-

mally swing slightly from side to side, the step 87 being confined only by the upper step of the slot 83, which is wider than the step 87. When, however, the hook 82 is pulled to the front, the spring 85 is compressed, and the step 87 settles into the bottom of the slot 83, where it fits snugly, and the hook is then locked against rotation. A gas burner 88 is provided on the finger hook to heat the iron in case electric power is not available.

In using the machine, the operator adjusts the electric current until the proper temperature of the irons is obtained, and then starts the machine, with, say, the fore-part iron in operative position. He sets the forepart edge all around, using the finger hook 82 as he rounds the toe, pulling it out into locked position, as soon as he touches it. When the fore part is finished, the operator presses the sole of the shoe against the head 79 without shifting his position on the floor. The lever 72 and its attached parts then unlock the tool holder from the rocker frame, and rotate it 180° as above described, 80 whereupon the operator releases his pressure on the head 79 and the tool holder settles back into locked relation with the rocker frame, with the shank iron in operative position. In setting the edge of the shank the 85 hook 82 tips to one side or the other to permit that part of the shank adjacent to the breast to be set without interference between the heel and finger hook. The resilient mounting of the irons permits them to move 90 in paths which conform to the shape of the sole edge more closely than do the arcs of circles in which they oscillate when no pressure is being exerted against them.

The novel electric heating unit disclosed 105 herein is claimed in my divisional application Serial No. 36,721, filed June 28, 1915, and is therefore not claimed herein.

Having described my invention, what I claim as new and desire to secure by Letters 110 Patent of the United States is:—

1. A machine of the class described having, in combination, a rocker frame, a tool holder tiltably and rotatably mounted thereon, a plurality of burnishing tools mounted 115 on said holder and mechanism for tilting and subsequently rotating said holder whereby the positions of the tools are interchanged.

2. A machine of the class described having, in combination, a rocker frame, a carrier pivotally attached thereto, a tool holder having a plurality of tools thereon pivotally mounted in said carrier, and a lock for said tool holder, operable by the 120 pivotal motion of the carrier.

3. A machine of the class described having, in combination, a rocker frame, a tool holder attached thereto, and constructed and arranged to yield pivotally under the 130

- pressure of the work, a plurality of tools carried by said holder and a latch whereby said tool holder is resiliently held in operating position.
5. A machine of the class described having, in combination, a shaft, a tool carrying head mounted on said shaft, a tool holder pivoted to said head, and a resilient contact member for said holder confined in said 10 shaft by said head.
5. A machine of the class described having, in combination, a rocker frame, a burnishing mechanism mounted to rotate into locked and unlocked relation with said 15 frame and having a plurality of operative positions, and means for unlocking said mechanism and for shifting it from one operative position to another, said means engaging said mechanism substantially in the 20 axis of oscillation of said rocker frame.
6. A machine of the class described, having, in combination, a rocker frame, a burnishing mechanism having a plurality of operative positions and a member constructed and arranged to lock said mechanism in 25 position on said rocker frame and resiliently cushion said mechanism.
7. A machine of the class described having, in combination, a rocker frame, a burnishing mechanism having a plurality of operative positions and an adjustably resilient device on the rocker frame constructed and arranged to latch and cushion said mechanism.
- 30 8. A machine of the class described having, in combination, a rocker frame, a tool holder tiltably and rotatably mounted thereon and carrying a plurality of tools, and a single mechanism constructed and arranged 35 to lock said holder against rotation and to hold the same resiliently against tilting.
9. A machine of the class described having, in combination, a rocker frame, a carrier, a tool holder, means for locking the 40 holder to the rocker frame and means for changing the angular relation of the holder and carrier.
10. A machine of the class described having, in combination, a rocker frame, a tool 45 holder mounted on said rocker frame to pivot about two axes, and means for turning said tool holder about both of said axes.
11. A machine of the class described having, in combination, a rocker frame, a carrier pivotally mounted upon said frame, a 50 tool holder movably mounted upon said carrier, and means on said rocker frame to lock said tool holder against motion relative to 55 said carrier.
12. A machine of the class described having, in combination, a rocker frame, a tool holder mounted to rotate about two axes with respect to said frame, and means nor- 60 mally preventing rotation about one of said axes, so constructed and arranged to oppose resiliently rotation about the other of said axes.
13. A machine of the class described having, in combination, a rocker frame, a carrier, a tool holder movable relative to the carrier into different operative positions, and means for positively moving said holder from one operative position to another, said holder being rotatable into and out of locking engagement with said rocker frame. 70
14. A machine of the class described having, in combination, a rocker frame, a carrier pivotally mounted thereon, a tool holder rocking with said frame, and movable relative to said frame into different operative positions, and a resilient locking member normally engaging said holder, so constructed and arranged as to disengage it by motion of the carrier in one direction about its 80 pivotal mounting, and resiliently permit motion of the carrier in the other direction about its pivotal mounting. 85
15. A machine of the class described having, in combination, a rocker frame, a tool holder movable relative thereto into different operative positions, and rotatable into and out of interlocking engagement with said frame, and an actuating device located close to the position occupied by the shoe 90 when in burnishing position and arranged to be operated by a bodily movement of the shoe out of burnishing position and into engagement with said device, and means intermediate said device and tool holder arranged to transmit the motion of said actuator to said holder to rotate it out of said interlocking engagement and to move the holder to another operative position. 95
16. A machine of the class described having, in combination, a rocker frame, a tool holder movable relative thereto into a plurality of operative positions, and an actuating device for moving said holder from one operative position to another, comprising a stop for arresting the motion of the tool holder when another operative position has been reached. 100
17. A machine of the class described having, in combination, a tool holder, having a plurality of operative positions, a lever for moving said holder from one operative position to another, and a stop carried by said lever to contact with said holder when said other position has been reached. 115
18. A machine of the class described having, in combination, a finger rest, and means whereby said rest is locked against rotary movement when operated by the workman and is unlocked and free to move at other 110 times. 120
19. A machine of the class described having, in combination, a finger rest, and means

whereby said rest is locked against rotary movement when used by the operator and is automatically unlocked when released.

20. A machine of the class described having, in combination, a movably mounted finger rest and means operated by the stress incident to the operator's use of it for locking said rest against rotary movement.

21. A machine of the class described having, in combination, a movably mounted finger rest, and means engageable with said rest for limiting its freedom of movement, said rest being moved into engagement with said means by the force exerted by the operator in using it.

22. A machine of the class described having, in combination, a movably mounted finger rest, constructed to move resiliently under the force exerted upon it by the operator in using it, and interlocking means so arranged as to become effective upon said resilient motion whereby said rest is locked when in use against movement in directions other than in the line of said resilient movement.

23. A machine of the class described having, in combination, an element having a slot and arranged adjacent the position of the shoe which is being burnished, a finger rest movably mounted in said element, a lug on said rest adjacent to said slot, and means for normally holding said lug disengaged from said slot.

24. A machine of the class described having, in combination, an element arranged adjacent to the position of the shoe which is being burnished, a finger rest so mounted in said element as to permit motions of rotation and translation therein and means whereby one of said motions inhibits the other.

25. A machine of the class described having, in combination, a member arranged adjacent to the position of the shoe which is being burnished, a finger rest movably mounted in said member, a lug on one of said members, the other of said members having a slot, and means for normally holding said lug disengaged from said slot.

26. A machine of the class described having, in combination, an oscillatory tool carrier having a spindle mounted therein, and a plurality of burnishing tools mounted on the spindle, the tool carrier having a socket constructed and arranged to hold an electric unit for heating the tools which unit is simi-

lar in shape to the spindle and arranged in close relation thereto throughout its extent, whereby wasteful radiation from the unit is minimized.

27. In a machine of the class described, a tool carrier, a holder carrying a plurality of tools mounted in said carrier and arranged to be moved into a plurality of positions corresponding to operative positions of the several tools, and an electric heating unit, said unit being similar in shape to an adjacent portion of the holder and the unit and portion being correspondingly placed, whereby undue waste of heat is avoided in heating the holder and tools carried thereby.

28. A machine of the class described having, in combination, shoe treating mechanism, a finger rest constructed and arranged to move freely laterally in order to avoid contact with the heel of the shoe when the rest is not in use, and means for inhibiting the lateral movement, said means being independent of the treating mechanism.

29. A machine of the class described having, in combination, shoe treating mechanism, a finger rest constructed and arranged to move freely laterally in order to avoid contact with the heel of the shoe when the rest is not in use, and means for inhibiting the lateral movement, said means being independently operable by the workman.

30. A machine of the class described having, in combination, a finger rest constructed and arranged to move freely laterally to avoid contact with the heel of the shoe when the rest is not in use, and means for inhibiting the lateral movement when the rest is in use, said means being placed in operation by stress imparted by the operator while using the rest.

31. In a burnishing machine, a burnishing tool, a finger rest adjustably mounted near said tool and constructed and arranged to be normally free to move laterally out of operative relation to said tool and to be locked in operative relation to said tool by the operator.

In testimony whereof I have signed my name to this specification in the presence of two subscribing witnesses.

FREDERICK M. FURBER.
